United States Patent Office

Des. 201,778
Patented July 27, 1965

201,778

JOINTED MANNEQUIN OR SIMILAR ARTICLE

Irving Berman, New York, N.Y.
(97-12 69th Ave., Forest Hills, N.Y.)

Filed Dec. 6, 1963, Ser. No. 77,696

Term of patent 14 years

(Cl. D80—8)

Fig. 1

Fig. 2

FIGURES 4 and 5 are front elevational views of the jointed mannequin of FIGURE 1 showing the jointed parts of my new design in different positions.

I claim:

The ornamental design for a jointed mannequin or similar article, substantially as shown.
